UNITED STATES PATENT OFFICE.

ISADORE BERGER, OF NEWARK, NEW JERSEY, ASSIGNOR TO ELIZABETH H. CHEIN, OF NEW YORK, N. Y.

WHEELED TOY.

Application filed August 28, 1926. Serial No. 132,097.

My invention is a new and useful improvement in wheeled toys and relates more particularly to the driving mechanism therefor.

- 5 An object of my invention is to provide a sheet metal toy of simple construction and attractive outline such as a trolley car or automobile or a representation of any well known wheeled device.
- 10 Another object is to provide a novel driving mechanism for the toy which has a locking means to prevent rotation of the driving wheels when the same are out of contact with the supporting surface for the toy.
- 15 The invention consists in the improved construction of parts and elements, and their aggroupment in operative relation, to be more fully described hereinafter and the novelty of which will be particularly pointed out and distinctly claimed.

I have fully and clearly illustrated a preferred embodiment of my invention in the accompanying drawings to be taken as a part of this specification, and in which

- 25 Figure 1 is a side elevation of the toy with parts broken away,

Figure 2 is a plan view of the driving mechanism,

- 30 Figure 3 is a detail section on the line 3—3 of Figure 2, and

Figure 4 is a detail of the blank from which the support for the driving mechanism is formed.

Similar characters of reference refer to 35 similar parts throughout the several views.

The numeral 1 designates a wheeled toy which is here shown in the form of a trolley car. The toy is preferably made of sheet metal, though any suitable material 40 may be employed in its construction. The car 1 has the usual trolley pole 2 and pulley 3 mounted thereon. The body 4 is mounted on wheels 5, 5 which are supported in journal bearings bent from the support 6, as 45 7, 7.

The support 6 has lugs or ears 8, 8 extending outwardly from its sides in the plane of the bottom 9. These lugs engage the body 4 to retain the support 6 in place in the body 4 when the toy is assembled. The sides 50 10, 11 of the support are bent upwardly and are provided with diametrically opposed sets of bearings 12, 12 and 13, 13 in which the shafts 14, 15 of the driving mechanism 55 are mounted. A pawl 16 is bent from the

side 11 of the support to lie in the path of a ratchet wheel 17 which is fixed to the shaft 14. A semi-annular portion 18 which lies adjacent the journal bearing 7 of one of the driving wheels 5 is cut and bent from the bottom 9 to lie in spaced parallel relation to the bearing 7. The upper or inner edge 19 of the portion 18 is provided with a tooth 20 for a purpose to be presently described.

The bearing 7 which lies adjacent the portion 18 has an elongated slot to receive the axle 22 as distinguished from the circular bearing for the other end of the said axle. The slot 21 is vertical when the wheels 5, 5 are upon a horizontal surface and it is therefore evident that the end of the shaft or axle 22 will be movable to the top of the slot when the wheels 5, 5 carry the weight of the car. The weight of a single wheel 5 is sufficient however to carry the axle 22 to the bottom of the slot 21. The axle 22 is square or rectangular intermediate its ends to receive a detent or catch 23 and hold the same in positive fixed relation to its shaft 22. The detent is positioned on the shaft so as to overlie the portion 18. The detent is preferably made substantially U-shaped in cross-section as is clear from Figure 2 so that the base of the U portion will engage the tooth 20 during one direction of rotation of the shaft when the shaft is at the base of the slot 21, to prevent rotation of the shaft 22.

The shaft 14 is provided with a coil spring 24 which is fixed at 25 to the ratchet wheel 17 and at 26 to the gear wheel 27. A compound gear 28 on the shaft 15 engages gear wheel 27 and also a cog or pinion 29 on the axle 22 so that energy stored in the spring 24 will be imparted to the wheels, 5, 5 on the axle 22 to rotate the same and drive the car 1.

The operation of the mechanism is as follows: The car is raised from the floor for winding, immediately the detent 23 will drop into engagement with the tooth 20 and the spring 24 may be wound up by the key 30 without the necessity of holding the wheels 5, 5. Now when the spring has been wound and is held under tension between pawl 16 and detent 23 it may be released by raising the wheels or the axle which carries them and the detent 23 to thereby move the detent out of contact with the tooth 20 and release the spring 24. It is of course 110

evident that this would be accomplished by placing the car on the floor or otherwise supporting the car on its wheels.

Having thus described my invention, I claim:

1. A wheeled toy including a support, journal bearings depending from said support, an axle journaled in said bearings, one of said bearings being vertically slotted, surface engaging wheels fixed on said axle, a semi-annular portion depending from said support adjacent said one bearing and substantially parallel thereto, said portion having a tooth on its inner periphery, and a detent carried by said axle in the plane of said portion.
2. A wheeled toy including a support, pairs of journaled bearings depending from

said support, an axle journaled in each pair of bearings, a pair of surface engaging wheels on each said axle, one of said bearings being slotted for vertical movement of the axle journaled therein, a semi-annular portion depending from said support around said vertically movable axle, a tooth on the inner periphery of said portion, and a substantially U-shaped detent fixed on said vertically movable axle substantially in the plane of said portion, said detent being adapted to engage said tooth when said vertically movable axle is at the bottom of said slotted bearing.

In testimony whereof, I have signed my name to this specification this 24th day of August, 1926.

ISADORE BERGER.
